D. HALPERN

PERMANENT WAVING ATTACHMENT

Filed Feb. 11, 1928

D. Halpern
Inventor
By attorney M. L. Beale

UNITED STATES PATENT OFFICE.

DAVID HALPERN, OF BROOKLYN, NEW YORK, ASSIGNOR TO HYMAN & OPPENHEIM, OF NEW YORK, N. Y., A CORPORATION OF NEW YORK.

PERMANENT-WAVING ATTACHMENT.

Application filed February 11, 1928. Serial No. 253,560.

This invention relates to hair curling devices.

Among the objects of the invention is to provide a device of the type set forth having improved means to permit the hair to be curled even at a point in close proximity to the roots of the hair.

Another object of the invention is to provide a device of the character described in which a hair clamp is associated in an improved manner with a hair curler that permits the hair to be tightly wound to any desired degree, and curled to a point closer to the head than has heretofore been possible.

A further object of the invention is the production of a device of the class specified, which is simple and inexpensive in construction, comprises few parts, that are easy to operate, and which is efficient in use to a high degree.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings in which like reference characters designate the same parts in the several views, and in which—

Figure 1 is an elevational view showing the clamp in position on a lock of hair, and an initial step in the operation of the hair curler.

Fig. 2 is a similar view, showing the device completely attached, but with certain parts removed to show interior construction.

Fig. 3 is a right end view of the device shown in Fig. 2, with a heating appliance shown in dotted lines in position thereon.

Fig. 4 is a diagrammatic end view of a lock of hair showing how the same is wound for curling by my improved device.

Fig. 5 is an end view of a device upon which my invention is an improvement.

Fig. 6 illustrates diagrammatically the hair as wound thereby.

Fig. 7 is a section in elevation taken on the line 7—7 of Fig. 1.

Fig. 8 is an external plan view of a portion of the hair curler in open position.

Fig. 9 is a left end view of the member 55 shown in Fig. 8.

Fig. 10 is a side view of the clamp in open position.

Fig. 11 shows a lock of hair curled by my improved device.

Referring in detail to the drawings, 12 denotes a device embodying the invention. Said device includes a plurality of separate parts or units which are adapted for compact interengagement. Generally described, 66 A indicates a clamp for receiving a lock of hair L adjacent to a person's scalp or head H. The lock of hair is wound about a member B, with the use of paper in a well known manner. When the winding has been completed, the member B is alongside the clamp A. Thereafter, the cover C is slipped over the coil of hair on member B. The cover interlocks with portions carried by the clamp, and has pawl and ratchet engagement with the member B. The said cover C now constitutes an anchorage with respect to which the member B may be rotated to tighten the coil of hair, and be retained by said cover against reverse movement. The member B and cover C are now in central alignment with the clamp opening. The tension on the lock of hair is in opposed direction to the interlocking portions of the clamp, so that the action of said portions, is of a simplified character. Finally a heating appliance D of any type well known in the art is applied over the device 12.

More particularly described, the clamp A includes a plurality of jaws 13, 14. To these may be attached wooden strips 15 extending therealong, by any suitable means, as for example, prongs 15^a struck from the jaws. To the jaw 13 is rigidly secured a hinge member 16, the jaw 14 being pivoted to the latter at 17. A locking member 18 is pivotally connected at 19 to the jaw 13. The member 18 includes a pair of metal strips 18^a at opposite sides of the jaw 13. Between the said strips 18^a at the free ends thereof is mounted a lever 20 on a pin 21, the lever having a cam portion 20^a for a purpose soon to be described. When the clamp is closed, the end 14^a of the jaw 14 is received between the strips 18^a of the member 18, after which the lever 20 is swung counterclockwise causing cam 20^a to abut the side edge portion 14^b

of the jaw 14 and tightly closing the clamp. To guard against cutting the hair the said jaws are preferably lined with rubber 22 set into their longitudinal grooves 13⁵ and 14⁶.

The clamp A is provided with engaging members or hooks 23, 24 positioned at one side of the clamp at the ends of the same. The said hooks may be mounted directly on members 16 and 18, in rigid engagement therewith. Preferably, the hooks are formed of thin strips of metal as shown in Fig. 7. These strips are bent at 24 to comprise side portions 25 extending along the respective members 16 and 18 and secured thereto by the pivot and engaging pins shown at the ends of said members. The bends 24 provide reversely extending portions 26 parallel to the portions 25, the former portions terminating in the hooks 23 aforesaid.

The core B includes a tube 27, which gradually decreases in diameter from each end toward the center thereof. An arm 28 of arcuate cross section is pivotally mounted at 29 at one end of the tube. The latter is provided with a coaxial ratchet wheel 30 in proximity to the pivot 29.

The cover C comprises a pair of members 31, 32, hingedly connected at 33. Mounted on the member 32 is a spring pawl 34, secured to the same by eyelet fasteners 35. The said pawl engages the ratchet wheel 30, when the cover C is caused to embrace member A. Air holes in the form of eyelets 35^a are also provided.

A locking portion or engagement flange 36 is formed integrally on the cover member 32. The said flange extends along the member 32 and is bent outward therefrom as shown in Figs. 2 and 3. The companion cover member 31 is formed with integral outward extending flange portions 37 at its ends. Between the said flange portions, is a downward extending stop flange 38, which coacts in a manner hereinafter described.

The operation of the device will now be apparent. The clamp A is engaged over a lock of hair L adjacent to the roots of the hair. Then the member B is turned to cause the said lock to be wound thereon, bringing the said member alongside the clamp A. The cover C is next closed over the member B and the hair thereon. Simultaneously, the locking flange 36 is engaged with the hooks 23. Coincidentally, the flange portions 37 are seated on the hook carrying strips 26, and the stop flange 38 received between the said hook carrying strips to prevent endwise movement of the cover C with respect to the clamp A. The operator then manually turns the member B by taking hold of the ratchet wheel 30 between the fingers, and rotating the same. Thus any desired tension may be put on the hair.

Owing to the direction in which member B is rotated, the tension acts in opposed relation to the locking hooks 23, 24 and their coacting flange 36. The position of the said coacting parts is such that the member B 70 and cover C are disposed in central alignment with the opening in the clamp as is clearly shown in Fig. 3. Thus even those portions of the hair in close proximity to the head H are wound up for curling. The 75 form of the coil assumed by the lock of hair is shown in Fig. 4. Finally, the heater D is applied to give the lock of hair a fixed curled effect.

By the construction hereinbefore known, 80 after clamp A and member B had been applied to the hair, a cover C₁ was placed in position. On tightening the hair by rotation of the ratchet wheel 30 as above set forth, the parts B and C would be caused to 85 move laterally with respect to the central opening of the clamp, as shown in Fig. 5. This would result from a tangential pull of the hair on the member B. Further, a spring 40 would have to be applied over the 90 cover to cause the same to bind over the coil of hair and prevent any unwinding of same. The form of the coil of the lock of hair on member B, according to this construction, is shown in Fig. 6. The length of hair left 95 uncurled is shown at 41 as compared with 42 of the coil of Fig. 4.

I claim:

1. A device of the character described, including a clamp having elongated jaws in 100 which a lock of hair is adapted to be gripped adjacent to the roots of the hair, a core about which the lock of hair is wound, extending along said clamp, a sleeve to take around the said core, interlocking means between the core and sleeve to permit rotation of the core in one direction relative to the sleeve, for winding the hair on the core, but to prevent rotation of the core in an opposite direction, and stop means coacting 105 between the sleeve and the clamp to set the core in central relation to the opening between the jaws.

2. A device of the character described, including a clamp having elongated jaws in 115 which a lock of hair is adapted to be gripped adjacent to the roots of the hair, a core extending along the said clamp, about which the lock of hair is wound, and means acting between the clamp and the core to set the latter in central relation to the opening between said jaws.

3. A device of the character described, including a clamp having elongated jaws between which a lock of hair is adapted to be gripped in proximity to the roots of the hair, a core extending along the clamp, about which the hair is adapted to be wound, and means acting between the clamp and the core to cause the latter to retain the hair 125 130

wound thereon in close proximity to the clamp.

4. A device of the character described, including a clamp having elongated jaws between which a lock of hair is adapted to be gripped in proximity to the roots of the hair, a core extending along the clamp, about which the hair is adapted to be wound, and means acting between the clamp and the core to prevent the core from turning and the hair unwinding, said means serving to set the core in central relation to the opening between the jaws.

5. A device of the character described, including a clamp having elongated jaws between which a lock of hair is adapted to be gripped in proximity to the roots of the hair, a core extending along the clamp, about which the hair is adapted to be wound, and means acting between the core and the clamp to prevent the core from turning and the hair unwinding, to retain the hair in close proximity to the clamp, wound on said core.

6. A device of the character described, including a clamp having elongated jaws be-

tween which a lock of hair is adapted to be gripped in proximity to the roots of the hair, a core extending along the clamp, upon which the hair is adapted to be wound, and means acting between the clamp and the core to prevent the core from turning and the hair unwinding.

7. A device of the character described, including a clamp having elongated jaws between which a lock of hair is adapted to be gripped in proximity to the roots of the hair, a core extending along the clamp, about which the hair is adapted to be wound, a sleeve to take around said core, interlocking means between the core and sleeve to permit rotation of the core in one direction relative to the sleeve, for winding hair on the core, but to prevent rotation of the core in an opposite direction, and means coacting between the sleeve and the clamp to detachably secure the sleeve in central relation to the opening between the jaws.

In testimony whereof I affix my signature.

DAVID HALPERN.

DISCLAIMER

1,673,942.—*David Halpern*, Brooklyn, N. Y. PERMANENT-WAVING ATTACHMENT. Patent dated June 19, 1928. Disclaimer filed April 4, 1933, by the assignee, *The Philad Company*.

Disclaimer is hereby entered to claims 2, 3, 4, 5, and 6 in the above identified Letters Patent, the said claims being in the following words, to wit:

“2. A device of the character described, including a clamp having elongated jaws in which a lock of hair is adapted to be gripped adjacent to the roots of the hair, a core extending along the said clamp, about which the lock of hair is wound, and means acting between the clamp and the core to set the latter in central relation to the opening between said jaws.

“3. A device of the character described, including a clamp having elongated jaws between which a lock of hair is adapted to be gripped in proximity to the roots of the hair, a core extending along the clamp, about which the hair is adapted to be wound, and means acting between the clamp and the core to cause the latter to retain the hair wound thereon in close proximity to the clamp.

“4. A device of the character described, including a clamp having elongated jaws between which a lock of hair is adapted to be gripped in proximity to the roots of the hair, a core extending along the clamp, about which the hair is adapted to be wound, and means acting between the clamp and the core to prevent the core from turning and hair unwinding, said means serving to set the core in central relation to the opening between the jaws.

“5. A device of the character described, including a clamp having elongated jaws between which a lock of hair is adapted to be gripped in proximity to the roots of the hair, a core extending along the clamp, about which the hair is adapted to be wound, and means acting between the core and the clamp to prevent the core from turning and the hair unwinding, to retain the hair in close proximity to the clamp, wound on said core.

“6. A device of the character described, including a clamp having elongated jaws between which a lock of hair is adapted to be gripped in proximity to the roots of the hair, a core extending along the clamp, upon which the hair is adapted to be wound, and means acting between the clamp and the core to prevent the core from turning and the hair unwinding.”

[Official Gazette April 25, 1933.]

wound thereon in close proximity to the clamp.

4. A device of the character described, including a clamp having elongated jaws between which a lock of hair is adapted to be gripped in proximity to the roots of the hair, a core extending along the clamp, about which the hair is adapted to be wound, and means acting between the clamp and the core to prevent the core from turning and the hair unwinding, said means serving to set the core in central relation to the opening between the jaws.

5. A device of the character described, including a clamp having elongated jaws between which a lock of hair is adapted to be gripped in proximity to the roots of the hair, a core extending along the clamp, about which the hair is adapted to be wound, and means acting between the core and the clamp to prevent the core from turning and the hair unwinding, to retain the hair in close proximity to the clamp, wound on said core.

6. A device of the character described, including a clamp having elongated jaws be-

tween which a lock of hair is adapted to be gripped in proximity to the roots of the hair, a core extending along the clamp, upon which the hair is adapted to be wound, and means acting between the clamp and the core to prevent the core from turning and the hair unwinding.

7. A device of the character described, including a clamp having elongated jaws between which a lock of hair is adapted to be gripped in proximity to the roots of the hair, a core extending along the clamp, about which the hair is adapted to be wound, a sleeve to take around said core, interlocking means between the core and sleeve to permit rotation of the core in one direction relative to the sleeve, for winding hair on the core, but to prevent rotation of the core in an opposite direction, and means coacting between the sleeve and the clamp to detachably secure the sleeve in central relation to the opening between the jaws.

In testimony whereof I affix my signature.

DAVID HALPERN.
